UNITED STATES PATENT OFFICE.

NATHANIEL C. STAMPS, OF LOS ANGELES, CALIFORNIA.

CARBURETER.

1,140,722.

Specification of Letters Patent. Patented May 25, 1915.

Application filed February 24, 1912. Serial No. 679,684.

To all whom it may concern:

Be it known that I, NATHANIEL C. STAMPS, a citizen of the United States, residing at Los Angeles, in the county of Los Angeles and State of California, have invented new and useful Improvements in Carbureters, of which the following is a specification.

This invention relates to improvements in carbureters and particularly such as are useful in connection with explosive gas engines used upon auto vehicles, aeroplanes or the like.

It is an object of the invention to provide a carbureter for explosive engines in which the gasolene and air feed as well as the throttle mechanism are at all times under a positive control for delivering their proportionate quantities of materials.

It is a further object of the invention to provide a carbureter which may be set at low speed for starting the operation of the engine and which is provided with an air controlling inlet, adapted to be positively operated in connection with the throttle mechanism and which is also capable of correspondingly increasing the flow of gasolene.

It is a still further object of the invention to provide such a mechanism with means to facilitate the starting of an aeroplane, where the throttle of the engine must be opened before the aeroplane is permitted to move and where the air supply should be somewhat modified beyond the normal arrangement of the device when the aeroplane is in movement.

In the accompanying drawing forming a part of this specification, Figure 1 is a view partially in section and partially in side elevation of the improved carbureter forming the subject matter of this invention, the float chamber and the gasolene supply valve being shown in section while the other portions are in elevation. Fig. 2 is a transverse vertical sectional view through the mixing chamber and the throttle mechanism. Fig. 3 is a detail sectional view taken upon the line 3-3 of Fig. 1. Fig. 4 is a sectional view taken upon the line 4-4 of Fig. 1, adjacent portions of the mechanism being shown in elevation. Fig. 5 is a side elevation of the upper part of the carbureter looking at the inlet end of the auxiliary air supply. Fig. 6 is a fragmentary detail sectional view taken through the walls of the mixing

chamber and showing the adjustable slides controlling the air inlets thereto, the adjustable place for operating the gasolene inlet being illustrated in top plan view. Fig. 7 is a detail sectional view through the by-pass mechanism for permitting of the priming of the engine around the throttle valve.

This invention is for a device similar to that described and claimed by me in application filed by me on Aug. 7, 1911, bearing S. N. 642,761, and the present device is an improvement upon the carbureter disclosed in that application.

The details and features of the invention will now be more particularly described, reference being had to the said drawing in which—

10 indicates a casing having a passage 11 formed therein, the said passage being open to the atmosphere at one end while the other end leads into the mixing chamber of the device. The passage is formed with a centrally depressed portion 12 forming a goose neck and a partition 13 extends downwardly into said goose neck to a point near the bottom of the passage. A bearing 14 is formed centrally of said partition to receive a needle valve 15 which controls the inlet of gasolene to the carbureter from the float chamber.

The device is provided with the usual float chamber 16 having a float 17 therein, adapted to operate a valve controlling lever 18. The said lever controls a gasolene supply valve 19 in the usual manner. Gasolene is introduced from the float chamber to the goose neck 12 through a passage 20, which is normally controlled at its upper end by a tapered portion of the needle valve. The goose neck is also provided with an overflow pipe 21, which directs any surplus gasolene through a bore 22 formed in the casing and which will lead the same outside the mechanism. The upper portion of the needle valve passes through a chamber 23 formed in the casing 10 and a spring 24 surrounds the said needle valve bearing at its lower end against a collar 25 formed upon the valve, so as to tend to push the valve to its seat, while the upper end bears against a removable plug 26 inserted in the upper end of the said chamber 23 and adapted to close the same. The said needle valve projects through said plug and is formed with an upper screw threaded portion 27, which adjustably engages a transverse bar 28.

The upper end of the needle valve is formed with a milled head 29 by which it may be turned when it is necessary to adjust it with respect to the bar 28. The 5 said bar 28 is employed to lift the needle valve to a proper extent, for feeding the required amounts of gasolene to the carbureter from time to time. The said bar is provided with reduced end portions which project in opposite directions therefrom and are 10 provided at their outer ends with anti-friction rollers 30 and 31 for guiding the movement of said bar. The roller 30 engages a bifurcated projection 32 which rises from the casing 10. The friction wheel 31 engages a slot 34 formed in a bar arranged upon the side of the upper part of the casing. In this manner the said bar 28 is positively guided in its vertical movement in 15 raising or lowering the needle valve, so that there can be no possible binding action in the movement of the needle valve. One end of the bar 28 also carries a roller 35 which engages an adjustable lifting plate, which 20 will be hereinafter described whereby the movement of the needle valve is positively controlled. A valve lifting means is also provided, comprising an arm 36 which is connected with and operated by a lever 37. 25 The said lever 37 is pivoted at 38 to the bifurcated projection 32 and its outer free end engages the groove of a collar 40 which is secured to an operating rod 41. The said operating rod 41 moves in any suitable bearing, usually afforded by a tube 42 and extends to any desired point for manipulation by the operator of the engine. The said arm 36 projects beneath an antifriction roller 43 mounted upon the side of the bar 40, so that when the rod 41 is pulled upon, the said arm 36 may be caused to lift the needle valve and thus supply additional gasolene to the carbureter.

The air which is drawn into the carbureter through the passage 11 and the goose neck 12, takes up any gasolene in the goose neck and passes thence into the bottom of the mixing chamber 44 through an opening 45. The floor of said mixing chamber 44 is 45 curved downwardly and made to converge to the said opening 45, so that any slight collections of gasolene within the mixing chamber will always be directed back into the incoming stream of carbureted air. By 50 this construction it is impossible for the carbureter to become clogged or flooded in the mixing chamber.

The mixing chamber is formed of a considerably greater diameter than the inlet 55 opening 45 and is provided with vertical walls for a portion of its height which are apertured at 46 for the inlet of air. Above said vertical wall portion the mixing chamber is contracted until a proper sized passage 47 is formed for the reception of the

throttle valve 48. The formation of the said mixing chamber and the throttle valve passage is similar to that described in my previous application already referred to. Mounted transversely of the passage 47 is a 70 shaft 49, which carries a throttle valve 48. The ends of said shaft 49 project beyond the walls of the passage 47 and an operating lever 50 is secured to one end of said shaft, while the opposite end carries an arm 51 75 which is adapted for operating the means which controls the air openings 46 in the walls of the mixing chamber. The said openings 46 are controlled by means of cylindrical slide plates 52 and 53, the said plates being formed with openings which can be brought into coincidence with the openings 46 for the admission of air. The two slides 52 and 53 are normally moved with their apertures 54 and 55 in coincidence 80 with each other so that when they are brought opposite the openings 46, the said openings may be uncovered to a greater or less degree. The inner slide 52 is provided with a flange 56 extending along its upper edge by which it may be turned, an arm 57 projecting therefrom at one point and being connected with the arm 51 by means of a link 58. The said link 58 is provided with ball and socket connections 59 and 60 at its ends and by which it is movably connected with the said arms 51 and 57.

The outer plate 53 is held in its normal relation to the inner plate 52 by means of a spring 61, the lower end of which is connected with a projection 62 carried by said plate 53 while its upper end is connected with the outer end of the said arm 51. The said plate 53 is also provided with an arm 63, by which it may be positively turned when desired against the action of the spring 61. The said arm 63 also carries a lug 64 which bears against an adjusting screw 65 carried by a depending standard 66, which projects from the said arm 57 of 100 the plate 52. It will be seen by reference to Fig. 1 that the said spring 61 tends to hold the lug 64 against the adjusting screw 65 and when in this position the apertures 54 and 55 of the two plates 52 and 53 coincide. 105

A rod 67 is provided and connected with the outer end of the arm 63 so as to permit the holding or movement of the plate 53 against the action of the spring 61 when the opening of the apertures 46 is to be prevented. This is desirable at times and particularly in the starting of gas engines which are employed upon aeroplanes. In starting aeroplanes the engine usually has to be operated with the throttle open and at 110 first it is not desired to have as much air admitted, as would normally be admitted by the mechanism of the present device when the throttle is open. As soon as the parts are in normal running condition the rod 67 115

may be released and the spring 61 will then cause the automatic operation of the outer plate 53 with the inner plate 52.

The movement of the plate 52 for introducing air is positively controlled in relation to the movement of the throttle through the agency of the link 58. The inlet of gasoline is also positively controlled in proper proportion to the amount of air entering the carburetor, by means of a cam plate 68 which is adjustably mounted upon a widened portion of the flange 56. One end of the said plate 68 is secured to the said flange by means of set screws 69 which engage a slot 70. The slot is sufficiently elongated to permit of a slight adjustment of the plate in putting it in place. The said plate is also adjustably held at intermediate points by means of set screws 71, 72, 73 and 74. Each 20 of said set screws, except the screw 71, engages a screw threaded opening formed in the flange 56 and the upper end of each screw projects upwardly through the same and is formed with an annular groove 75, 25 adapted to engage a slot 76 arranged opposite thereto. Each of the said slots 76 is made with enlarged end portions as shown in Fig. 6 so that the ends of the screws may be inserted therein in assembling the parts 30 and the annular grooves be caused to engage the reduced ends of said slots. It will be understood that by turning the screws in their threaded apertures on the flange 56, the extent to which the plate 68 is raised 35 above the said flange 56 may be determined.

The screw 71 is connected with the plate 68 in like manner as the screws 72, 73 and 74, but instead of engaging a screw threaded aperture in the flange 56, it passes through 40 a slot 78 in the said flange so as to be adjustable therein and carries a nut 79 below the said flange. The said nut 79 is located so closely to the slide 53 that it will not turn but the screw 71 may be turned for clamping 45 the plate 68 to the said flange 56. By this construction it will be seen that the screw 71 may be moved so as to draw the said cam plate 68 downwardly at one point or may be moved along in the slot 78 to 50 draw it down at another point so that the exact point at which the said cam plate begins to raise the roller 35, for accomplishing the introduction of gasoline past the needle valve may be altered and accurately 55 provided for. Thus the exact time when the carburetor begins to take gasoline is susceptible of a nice adjustment. It will also be understood that the precise curvature of the plate and its intermediate inclination 60 may be accurately determined by the said screws so that the gasoline controlling needle valve 15 will be raised in exact correspondence with the inlet of air through the openings in the walls of the mixing 65 chamber. It will be observed that as the

throttle valve is open and the slides begin to open the air inlets, that the roller 35 will be caused to ride upwardly upon the said cam plate 68 for introducing more and more gasoline.

After an engine has been speeded to a high rate, the inflow of gasoline due to the suction is somewhat increased above that which is desired and in order to obtain the full benefit thereof and the power which should be developed through its use, it is necessary to introduce additional air usually above the throttle valve. For this purpose the casing is formed with a passage 80 in the material of the casing around the upper portion of the passage 48 as clearly shown in Figs. 2 and 7. The said passage 80 is connected by apertures 81 with the throttle passage 47. Air is admitted to the passage 80 when desired by means of a series of passages 82 which extend through a projection 83 formed upon the carburetor casing. Near the outer ends of said apertures 80 a transverse valve 84 is mounted having passages 85 formed therein adapted to be brought into coincidence with the passages 82 when it is desired to admit air to the carburetor through the same. When the valve is turned to the position shown in Fig. 2, the entrance of air is cut off. One end of the said valve 84 is provided with an operating arm 86 outside the casing which is provided with a controlling rod 87 extending to any suitable or convenient point for use. The said rod 87 usually passes through a guide tube 88 which facilitates its proper action. Both of the said operating rods 41 and 87 are preferably made of steel wire such as piano wire and the guiding tubes 42 and 88 prevent them from doubling in use. Air introduced 105 through the apertures 82 is distributed by means of the circular passage 80 around the throttle passage so as to enter the same from all sides thereof. This arrangement is similar to the arrangement of the air inlets 46, 110 it being found that the introduction of air from the various sides of the chambers and passages of the carburetor tend to centralize the column of carbureted materials passing to the engine. The carburetor is also provided with means for directing priming gasoline to a suitable point adjacent to the throttle valve. For this purpose a by-pass passage 89 is formed in the casing of the throttle valve, its upper end being connected with the air passage 80 while its lower end is formed with an opening 90 connecting with the throttle passage below the throttle valve as clearly seen in Fig. 7. An adjusting screw 91 mounted in the casing is adapted to control the extent of opening at the said aperture 90. This by-pass connection facilitates the starting of the engine at low speed and affords a path for the carbureted material around the throttle valve, and the 115 120 125 130

3,149,198

throttle valve does not therefore have to be made so loose in the passage 47, but can be made to close the same snugly. Heretofore the throttle valve of a carburetor has usually been made of slightly less diameter than the passage in which it is located to permit of the passage by the same of the carbureted air in running an engine at low speed. A priming pipe 92 extends from the by-pass 89, at a point above the opening 90, downwardly outside the casing to the goose neck and then extends into the goose neck and to a point near the bottom thereof as clearly shown in Fig. 1. In starting the engine a priming of gasoline is introduced into the goose neck 12, the needle valve 15 of course being closed and the initial movement of the engine will, through its suction, draw the gasoline through the pipe 92 and through the by-pass 89 around the throttle mechanism and into the cylinders of the engine for starting the same. As soon as the engine is under way, the gasoline in the goose neck will be quickly taken up by the inrushing air and the lower end of said pipe 92 will thus be uncovered and a small quantity of air will pass through the same to the throttle mechanism.

The operation of the mechanism will be readily understood from the above description. In starting the engine as when in use upon an automobile, the priming is introduced into the goose neck in any desired manner and the engine is caused to take its initial movement. The priming will be drawn through the pipe 92, above the throttle valve and into the cylinders of the engine. The suction of the engine will immediately begin to draw air through the passage 11, taking up the gasoline from the goose neck and drawing in a mixture of air and gasoline through the mixing chamber. As the engine is to be speeded the lever 50 is operated for turning the throttle, and opening the same, the arm 51 and link 58 at the same time correspondingly moving slides 52 and 53 for admitting air through the several openings 46. The cam plate 68 will also be carried beneath the roller 35 to begin the elevation of the needle valve from its seat for the introduction of gasoline in correspondence with the amount of air fed into the mixing chamber. If, at any time, it is thought desirable to introduce more gasoline temporarily, the rod 41 is pulled upon thus lifting the needle valve 15 more than it would be lifted by the cam 68. In running the engine at very high speeds, additional air is also admitted above the throttle by operating the valve 84.

As already intimated, in using a gasoline engine for aeroplanes the engine is usually started with the throttle open and in this case it is desired at first to prevent a great deal of air entering through the

apertures 46 until the aeroplane is under way. In order to prevent the entrance of air at such time the rod 67 is operated to move the slide 53 against the action of the spring 61 and thus close to a greater or less degree apertures through which the air enters the mixing chamber. As soon as a proper action of the engine has been established however, the rod 67 is again released and the movement of the slides 52 and 53 becomes automatic in correspondence with the action of the throttle valve.

What I claim is:

1. A carburetor, comprising a casing having a gasoline inlet, a valve controlling the same, a mixing chamber having air inlet apertures in its walls, a throttle valve, an apertured slide for controlling the air inlet opening, means connecting the throttle valve with said slide, an adjustable cam plate carried by said slide, adapted to operate the needle valve for introducing more gasoline when the air inlets are opened by registering said apertures, and a lever manually operated independent of the slide for lifting said needle valve.

2. A carburetor, comprising a casing having a gasoline inlet, a needle valve controlling the same, a spring normally tending to close the same, a cam plate operable by the movement of the throttle mechanism of the engine for lifting the needle valve, and an auxiliary lifting means made up of an arm, means projecting from the needle valve engaging said arm, and means for operating said arm.

3. A carburetor, comprising a casing having a gasoline inlet and an air inlet, a mixing chamber connected with said air inlet and having air openings in its walls; a circular slide adapted to control said air openings and having openings in its walls, an auxiliary slide mounted outside the said circular slide and having openings, the first mentioned circular slide having a stud projecting therefrom, a lug carried upon the outer slide and adapted to engage said stud, a spring normally tending to hold the lug against said stud for holding the openings of the slide in coincidence, means for moving the outer slide against the action of the said spring for moving the slides with respect to each other, and means for moving the said slides in correspondence with the movement of the engine throttle mechanism.

4. A carburetor, comprising a casing having a circuitous passage therethrough, a gasoline feed controlling valve, a mixing chamber having two series of air inlets in its walls, a throttle valve mounted in the passage intermediate said series of air inlets to said mixing chamber, means for operating the gasoline valve, in accordance with the movement of the throttle mechanism, means for controlling the air inlets in accordance

with the movement of said throttle mechanism, a by-pass connecting the mixture passage on either side of the throttle, and means for carrying to and controlling a priming charge passed through said by-pass in starting the engine.

5. A carbureter, comprising a casing having an air and gasoline inlet, a valve controlling the inlet of gasoline, the air inlet 10 having a goose neck chamber therein adapted to receive a priming liquid, a priming mechanism, the casing being provided with a passage extending around said throttle mechanism, a priming feed pipe extending 15 from said passage to the goose neck of the air inlet, for directing the priming material to the passage around said throttle, and means for controlling the said throttle and gasoline inlet in accordance with each 20 other.

6. A carbureter, comprising a casing having a passage therethrough provided with a plurality of air inlets and a single mixture outlet, a fuel inlet adjacent the oppositely disposed end forming an air inlet of said passage from said outlet, a mixing chamber intermediate said fuel inlet and said mixture outlet, formed of an enlargement of said passage having two series of apertures 25 30 in its walls, oscillating apertured valves to

control the passage of air through said apertures, a throttle valve intermediate said series of apertures in said chamber, and means to operate said valves.

7. A carbureter, comprising a casing having a gasoline feed and an air feed, a needle valve controlling the gasoline feed, an adjustable cam plate adapted to lift the needle valve at a predetermined period, a slotted plate positively connected with the throttle 35 carrying said cam plate, screws adjustably supporting said cam plate in position, and capable of adjustment with respect to each other to vary the extent of movement of the needle valve, and a clamping screw adjustably carried in the slot of said plate upon which the cam plate is mounted adapted to draw the said cam plate tightly against the same at one point or another in accordance 40 45 with its adjustment for controlling the time when the needle valve begins to be raised from its seat.

In witness that I claim the foregoing I have hereunto subscribed my name this 16th day of February, 1912.
